UNITED STATES PATENT OFFICE

98,370

DESIGN FOR A MUSICAL INSTRUMENT

Vinola Seaver, Beloit, Wis.

Application November 9, 1935, Serial No. 59,831

Term of patent 7 years

To all whom it may concern:

Be it known that I, Vinola Seaver, a citizen of the United States, residing at Beloit, in the county of Rock and State of Wisconsin, have invented a new, original, and ornamental Design for a Musical Instrument, of which the following is a specification, reference being had to the accompanying drawing, forming part thereof.

I claim:—

The ornamental design for a musical instrument, as shown.

VINOLA SEAVER.
